UNITED STATES PATENT OFFICE.

WILLIAM C. McLAUGHLIN, OF CHICAGO, ILLINOIS, ASSIGNOR OF ONE-HALF TO FOR-REST E. ADAMS, OF CHICAGO, ILLINOIS.

DESIGN FOR A SMOKING STAND.

Application filed April 6, 1928. Serial No. 26,156. Term of patent 7 years.

To all whom it may concern:

Be it known that I, WILLIAM C. McLAUGHLIN, a citizen of the United States, residing at Chicago, in the county of Cook and State of Illinois, have invented a new, original, and ornamental Design for a Smoking Stand, of which the following is a specification, reference being had to the accompanying drawing, forming part thereof.

Fig. 2 is a rear elevation of the same.

I claim:

The ornamental design for a smoking stand as shown.

WM. C. McLAUGHLIN.
